UNITED STATES PATENT OFFICE

ANDREW P. HRADESKY, OF UNIONTOWN, PENNSYLVANIA

TRAIN-STOPPING DEVICE

Application filed November 23, 1928, Serial No. 321,401. Renewed June 2, 1930.

The present invention relates to improvements in train stopping devices, and has for its principal object to provide a means whereby a train, either freight or passenger, may be brought automatically and quickly to a standstill when rendered necessary through unforeseen circumstances.

The invention consists essentially in providing automatic means for cutting off the supply of steam from the boiler of the locomotive to the steam chests and simultaneously admitting air to the brake cylinders to apply the brakes whereby the train will be brought to a standstill.

15 A further object is to provide a train stopping device that includes a particular trip mechanism controlled from a remote point by the towerman so that said tripping mechanism may be set to effect the stopping of an approaching train in case of an emergency.

Still a further object is to provide a train stopping device of the above mentioned character that will at all times be positive and efficient in its operation, the same being further 25 of such construction as to permit the installation thereof on the train and also along the side of the rails of a trackway.

Other objects and advantages of the invention will become apparent from the following 30 description when taken in connection with the accompanying drawings.

In the accompanying drawings, wherein like reference characters indicate corresponding parts throughout the same:

35 Figure 1 is a top plan view showing the trip mechanism arranged adjacent the rails and also showing the actuating means for said trip mechanism.

Figure 2 is an elevational view of the 40 hinged connected treadles forming an important part of the tripping mechanism.

Figure 3 is a sectional view taken approximately on the line 3-3 of Figure 1 showing the treadle structure in end elevation.

45 Figure 4 is a detail perspective view of the rocker shaft also forming a part of the tripping mechanism.

Figure 5 is a sectional view through the 50 valve body associated with the steam line and also disclosing the horizontally disposed

valve that is associated with the rockable shaft operated by the tripping mechanism.

Figure 6 is a sectional view through a locomotive cab showing the mounting for the rockable valve carrying shaft and the depending arms at the outer ends of said shaft which are provided with rollers for cooperation with the tripping mechanism at the side of the rails, and

Figure 7 is a diagrammatic view showing the various connections for actuating the valves associated with the steam and air lines respectively.

In the drawings wherein for the purpose of illustration is shown the preferred embodiment of my invention, the numeral 1 designates the cross ties which support the parallel spaced rails 2 and 3 in the usual manner. Upon referring to Figure 1 it will be noted that certain of the crossties are of greater 70 length than others, and these longer crossties 4 support the tripping mechanism denoted generally by the numeral 5. This tripping mechanism includes a pair of longitudinally extending treadles 6 and 7 respectively 75 that are hingedly connected together at their adjacent ends as at 8, said treadles being disposed parallel with the rail 2 and the outer ends of these treadles are slidably and pivotally mounted in suitable brackets 9 arranged on the projecting ends of the longer ties 4. As is more clearly shown in Figure 2, each of the treadles may be reinforced on its underside.

Upon referring to Figure 3 it will be noted 85 that a crank 10 is connected with the outer end portion of each treadle for cooperation with the brackets 9, and normally the treadles 6 and 7 are disposed in a horizontal position, whereby the same are rendered inoperative.

A rock shaft 11 is journaled in suitable bearings attached to one of the intermediate ones of the longer cross ties 4 for disposition below the rails 2 and 3, and one end of this rock shaft is formed with a crank 12 that 90 is operatively connected with the hingedly connected ends of the treadles as at 13 while the other end of the rock shaft extends beyond the rail 3, and is formed with a laterally disposed portion 14 to which is connected an 100

operating rod or cable 15 that leads to a nearby tower (not shown), where the towerman may operate the same. The rod or cable 15 is guided over suitable guide rollers or pulleys 16 that are arranged at spaced intervals adjacent the rail 3 as shown in Figure 1. The steam pipe or line that extends from the boiler 17 of the locomotive is shown at 18 and branch pipes 19 provide a means of communication between the steam line 18 and the steam chests 20 as shown diagrammatically in Figure 7. The engineer's throttle valve arranged in the steam line in the usual manner is indicated at 21.

15 A cruciform shaped fitting 22 is interposed in the steam line 18 adjacent the boiler 17, the steam line having its sections connected with the vertical portions of the cruciform shaped fitting, as clearly indicated in Figure 5. This fitting 22 constitutes what I term as a valve body and arranged horizontally through the valve body is the rocker shaft 23, a rotary valve 24 being arranged at the intermediate portion of this rocker shaft for rotation within the valve body 22 and this valve is formed with a transverse port 25 which is normally disposed vertically to afford communication between the sections of the steam line so that steam will be supplied to the steam chests in the usual manner.

An arm 26 extends downwardly from each end of the rocker shaft 23 and the lower end of each arm is formed with a fork within which is mounted for rotation a roller 27 that is adapted to cooperate with the tripping mechanism 5 in the manner to be presently described.

Upon referring to Figure 6 it will be observed that the rocker shaft 23 extends horizontally through the opposite sides of the cab of a locomotive, and this shaft is journaled in suitable bearings 28 arranged on the upper ends of the standards 29.

45 A vertically disposed lever 30 is secured at its intermediate portion on the rocker shaft 23 for movement therewith.

The brake cylinders that form a part of the air brake system of the train are shown at 31 and air is supplied to these cylinders for actuating the brakes through the pipes 32 and a rotary valve unit 33 is arranged in the air line 32, the stem of the plug of said air valve being shown at 34 and carried by the outer end of this stem is the lever 35. The lever is secured at its intermediate portion on the stem 34 and is normally disposed vertically. Air is supplied to the line 32 from any suitable source.

60 The invention further comprehends the provision of a segmental notched bar 36 that is formed in its upper edge with the spaced notches 37 with which cooperate the spring pressed pawl or dog 38 carried on the lower end of a rod 39; the upper end of the rod 65 being operatively connected with an auxiliary

handle 40 and this handle is in turn pivotally secured on the upper end portion of a vertically swinging lever 41.

A rod 42 provides an operative connection between the lower ends of the vertically disposed levers 30 and 35, while a similar connection is provided between the upper ends of these levers as indicated at 43. In addition, the pivoted lever 41 is operatively connected with the upper end of the lever 35 through the medium of the connecting rod 44 as clearly illustrated in the diagrammatic illustration in Figure 7.

The operation of my improved train stopping device may be briefly stated as follows: Under normal conditions, the tripping mechanism 5 is disposed in a lowered inoperative position, and the valve 25 is opened, while the valve 33 is closed, thus permitting steam to enter the steam chests 20 through the steam line under the control of the engineer by reason of the throttle 21.

15 In case of an emergency, the towerman operates the rod 15 to actuate the rocker shaft 11 so that the crank 12 will operate the hingedly connected treadles 6 and 7 to swing the same upwardly to the position shown in Figure 2 so that said treadles will be in the path of movement of the adjacent arm 26. When

16 said treadles 6 and 7 are swung upwardly to that position shown in Figure 2, the cranks 10 connected with the outer end portion of each treadle for cooperation with the brackets 9 will slide inwardly toward the inner end of the bracket, and at the same time function as a pivot for the outer ends of said treadles. When a train is traveling in the direction indicated by the arrow in Figure 2, the roller 27 will strike the treadle 6 and this will result in the rocker shaft 23 being actuated so as to move the valve 25 to the position shown in Figure 5 thus cutting off communication between the boiler and the steam chest and simultaneously the connecting means between the levers 30 and 35 will operate the valve 33 to open the air line and cause air to enter the brake cylinder 31 and effect the actuation of the brake mechanism to bring the train to a standstill almost immediately. At the same time the lever 41 will be actuated to move the locking pawl or dog 38 into one of the notches 37 thereby holding the parts in their positions.

115 The parts are so constructed as to effect the stopping of the trains regardless of the direction in which the train is traveling, and a train stopping device of this character will at all times be positive and efficient in its operation as well as automatic. Furthermore a train stopping mechanism of this character can be installed at a very low cost and will not necessitate any material alterations to the parts of the train with which said device is to be associated.

120 The parts are so constructed as to effect the stopping of the trains regardless of the direction in which the train is traveling, and a train stopping device of this character will at all times be positive and efficient in its operation as well as automatic. Furthermore a train stopping mechanism of this character can be installed at a very low cost and will not necessitate any material alterations to the parts of the train with which said device is to be associated.

125 While I have shown the preferred em-

bodiment of my invention, it is to be understood that minor changes in the size, shape and arrangement of parts may be resorted to without departing from the spirit of the invention, and the scope of the appended claims.

Having thus described the invention, what I claim as new and desire to secure by Letters Patent is:—

1. In a train stopping device, the combination with the steam line and the air line of the air brake system of the train, a valve arranged in the air line, a valve casing arranged in the steam line, a rock shaft rockably mounted in said valve casing and extending outwardly of the casing at opposite sides of the casing, that portion of the rock shaft within said valve casing having a valve member formed thereon for controlling the passage of steam through said steam line, a lever mounted intermediate its ends on said rock shaft, a second lever mounted intermediate its ends on the stem of the valve in said air line, an operating connection between said levers, a tripping mechanism for disposition along the side of the track, an arm depending from said rock shaft for engagement with the tripper mechanism when the latter is set whereby said rock shaft will be actuated for moving the valve carried thereby to a closed position, and the valve in the air line to an open position, a notched bar, a pivotally mounted lever disposed in operative relation to said notched bar, an operating connection between said last mentioned lever and the lever mounted on the stem of the valve in said air line, whereby when the valve in the air line is moved to an opened position, said last mentioned lever will be rocked, and a spring pressed dog carried by said last mentioned lever, and adapted to engage with one of the notches in said notch bar for retaining said valves in their last mentioned position.

2. In a train stopping device, the combination with the steam line and air line of the air brake system of the train, a normally closed valve arranged in the air line, a valve casing arranged in the steam line, a rock shaft mounted in said valve casing and projecting therethrough, a normally open valve member formed on said rock shaft within said valve casing, a lever secured intermediate its ends to the stem of the first mentioned valve, a second lever secured intermediate its ends to said rock shaft exteriorly of the casing, an operating connection between said levers for simultaneously actuating said valves, a notched bar, a manually controlled operating lever pivotally mounted in operative relation to said notched bar, means operatively connecting said manually controlled lever with the first mentioned levers, an arm depending from the outer end of said rock shaft, a tripping mechanism for disposition alongside of the track, said arm adapted to engage with said tripping mechanism for moving said

rock shaft in one direction for simultaneously moving the valve carried thereby to a closed position and the valve in said air line to an open position, whereby said manually controlled lever will be rocked in one direction, a spring pressed dog carried by said manually controlled lever, and adapted to engage with a notch in said notched bar for retaining said valves in their last mentioned position, and said spring pressed dog adapted to frictionally engage with a smooth part of said notched bar when said manually controlled lever is moved in an opposite direction for retaining said valves in their normal positions, and means for setting the tripping mechanism.

In testimony whereof I affix my signature.
ANDREW P. HRADESKY.
